UNITED STATES PATENT OFFICE.

FRANCIS M. RYAN, OF EAST ORANGE, NEW JERSEY, ASSIGNOR TO WESTERN ELECTRIC COMPANY, INCORPORATED, OF NEW YORK, N. Y., A CORPORATION OF NEW YORK.

RADIO TRANSMISSION SYSTEM.

Application filed August 24, 1921. Serial No. 495,026.

To all whom it may concern:

Be it known that I, FRANCIS M. RYAN, a citizen of the United States, residing at East Orange, in the county of Essex, State of New Jersey, have invented certain new and useful Improvements in Radio Transmission Systems, of which the following is a full, clear, concise, and exact description.

This invention relates to radio transmission systems and more particularly to arrangements for excluding interfering energy therefrom.

A feature of the invention consists in the provision of a reactive trap circuit having extremely large impedance for undesired energy, but low impedance for energy of the desired frequency.

Another feature of the invention relates to the association of a reactive trap circuit with a loop receiving antenna in such manner as to permit the loop to have the greatest possible effective receiving inductance.

It is customary in duplex radio signaling to use different carrier frequency waves for outgoing and incoming transmission, in order to permit the receiving apparatus to discriminate against the locally radiated wave. An additional feature of the present invention consists in increasing the discrimination of the receiving apparatus against locally radiated waves by including therein a trap circuit which offers high impedance to these locally radiated waves.

According to this invention, a radio receiving system is provided with an antiresonant or tuned loop circuit tuned to the frequency of the carrier wave radiated by the local radio transmitting station and therefore serving to substantially exclude the locally radiated energy from the receiving system. A loop antenna is used and if the frequency of the locally radiated carrier wave is lower than that of the received wave, the trap circuit is placed in the primary receiving circuit in series with the loop antenna. If the frequency of the locally radiated carrier wave is higher than that of the received wave, the trap circuit is placed in the secondary circuit which is coupled to the primary circuit.

The novel features which are considered characteristic of the invention are set forth with particularity in the appended claims. The invention itself, however, both as to its organization and method of operation, to-

gether with further objects and advantages thereof, will best be understood by reference to the following description taken in connection with the accompanying drawing in which Fig. 1 illustrates diagrammatically the circuit arrangements which may be employed at one terminal of a radio toll link in carrying the invention into effect, and Fig. 2 the circuit arrangements at the other terminal of the same radio toll link.

Referring to Fig. 1, a signaling station 1 which may represent a local operator's station, a central exchange, or a subscriber's station, connected through an exchange, is associated with a line L_1 which connects the signaling station with the incoming and outgoing radio channels 3 and 4 by means of the well-known balanced transformer or hybrid coil 6 and the balancing network N. The outgoing radio channel together with the transmitting apparatus T_1 and radiating antenna 11, and the incoming radio channel together with receiving antenna 12, constitute the radio apparatus at one terminal of a radio toll link connecting the station 1 with a distant station.

The outgoing radio channel 4 includes an amplifier A, preferably although not necessarily of the well-known three-element vacuum tube type and a low pass filter LPF 85 from which the signaling currents or impulses originating at station 1 are transmitted to radio transmitting apparatus T_1 to cause correspondingly modified oscillations of frequency F_1 to be supplied to transmitting antenna 11 and radiated therefrom. The network N as in the ordinary case, is so designed as to simulate the impedance of line L_1 and its associated station at the frequencies of all of the currents transmitted over line L_1 . The low pass filter LPF may be of the general type described in the article "Carrier current telephony and telegraphy" at pages 311 and 312 of the Journal of the American Institute of Electrical Engineers, volume 40, No. 4, April 1921.

The local radio receiving antenna loop 12 is connected in series with a tuning condenser 13 and the primary winding of a transformer 14. A loop 15 also included serially in this circuit is tuned to the frequency F_1 and constitutes an anti-resonant or trap circuit for the oscillations radiated from the local transmitter T_1 . In practice, antenna 11 and 12 may be placed closely

adjacent or may be separated by a distance of several miles. It is desirable to make the effective receiving inductance of the antenna loop as great as possible and to tune the antenna circuit as a whole to the frequency F_2 of the incoming oscillations. This requires that trap circuit 15 should present a capacity reactance at the frequency F_2 or in other words, that the frequency of the incoming waves be higher than that of the locally radiated waves. It is accordingly possible to utilize the inductance of the primary circuit to the fullest advantage in the antenna loop itself. Tuning of the primary circuit to the frequency F_2 is accomplished by means of the variable capacity element 13.

Incoming oscillations received by the antenna or primary circuit are applied by means of transformer 14 to the secondary circuit 16 also tuned to the frequency F_2 and are impressed upon a demodulator D_1 together with oscillations of high frequency F_3 supplied by a local oscillator O . Demodulator D_1 which may be of any desired type functions in the same manner as the similarly designated element of United States patent to Osborne 1,361,487, patented December 7, 1920, to yield in its output circuit intermediate frequency oscillations of the frequency F_2-F_3 modulated or otherwise modified in the same manner as the received oscillations of frequency F_2 . The intermediate frequency oscillations are amplified by an intermediate frequency amplifier IFA which may include either a band pass filter or a low pass filter of the types described in the article "Carrier current telephony and telegraphy" previously mentioned. The amplifier and filter are designed to transmit oscillations of a band of frequencies of an extent at least equal to that of the original signaling currents by which the incoming carrier wave of frequency F_2 is modified. The intermediate frequency oscillations after modification and selection are impressed upon a second demodulator D_2 which serves to derive therefrom waves of the original signal current frequencies which after modification by an amplifier A and selection by a low pass filter LPF, similar to that in channel 4 are impressed upon line L_1 and transmitted to station 1.

Upon reference to Fig. 2 it will be noted that the arrangement and operation of the apparatus at the remote terminal of the radio toll link are in general the same as in the case of the terminal apparatus illustrated in Fig. 1. The station 2 which is connected by the radio toll link to station 1 is associated with a line L_2 , radio transmitting apparatus T_2 , receiving channel 3 and transmitting channel 4, similar to those of Fig. 1. The frequency of the carrier wave

produced by the apparatus T_2 and radiated by antenna 21 is of course F_2 , and that received by loop receiving antenna 22 is F_1 . The frequency F_4 of the oscillations of oscillator O_2 , may be such that $F_1-F_4 = 70$ F_2-F_3 , and in that case the elements connected between the demodulator D_1 and the hybrid coil 6 in receiving channel 3 of Fig. 2 may be exactly like the similarly designated elements in receiving channel 3 75 of Fig. 1. If F_4 does not have the particular value stated above, the apparatus in the receiving channel 3 of Fig. 2 will vary only in that it is particularly designed to transmit an intermediate frequency carrier wave 80 of frequency F_1-F_4 . The frequency F_2 of the locally radiated carrier wave is higher than the frequency F_1 of the received waves. A trap circuit 25 comprising a closed loop tuned to the frequency F_2 is connected in 85 series in the closed secondary circuit 26 which is tuned to the frequency F_1 of the received carrier waves. This trap circuit offers an inductive reactance at frequency F_1 and if introduced directly into the primary circuit of the loop antenna 22, would diminish by a certain amount the effective inductance which might otherwise be given the antenna loop. The arrangement of the trap circuits at the two stations permits 90 each loop antenna to have the greatest possible effective receiving inductance and does not interfere with sharp selectivity for the carrier wave to be received as has been 95 demonstrated in practice. 100

In a given example, the frequencies F_1 , F_2 , F_3 and F_4 may have the magnitudes 600 kilocycles, 750 kilocycles, 700 kilocycles and 550 kilocycles respectively. The intermediate frequency at each terminal will then 105 be 50 kilocycles. If the system is used for speech transmission, the intermediate frequency amplifier and any selective circuits associated with it must then be capable of transmitting a band of currents at least as 110 extensive as one side band of a speech modulated wave having a carrier frequency of 50 kilocycles.

The anti-resonant circuit offers substantially infinite impedance to currents of one frequency and very high impedance to currents of a considerable range of frequencies adjacent thereto. Energy of frequencies not substantially suppressed by the anti-resonant circuit may be combined by the 115 demodulator D_1 with oscillations from the local oscillator to produce difference frequency oscillations. These oscillations will, however, be excluded by the selective circuits of the intermediate frequency amplifier. 120 125

Although the invention has been described as embodied in a specific radio transmission system, it is capable of use generally in high frequency wave transmission. It is there- 130

fore to be limited only by the scope of the appended claims.

What is claimed is:

1. A carrier wave receiving system comprising a closed energy-receiving circuit, a secondary circuit connected thereto, and means having inductive reactance at desired frequencies in said secondary circuit for excluding energy of undesired frequency.
2. A carrier wave receiving system comprising a closed energy-receiving circuit, a secondary circuit coupled thereto and tuned to waves of a desired carrier frequency, and means having inductive reactance at desired frequencies in said secondary circuit for excluding energy of undesired frequency.
3. A radio receiving system comprising a closed antenna circuit, a secondary circuit connected thereto, and means having inductive reactance connected in one side of said secondary circuit for excluding energy of undesired frequency.
4. A radio receiving system comprising a closed antenna circuit, a secondary circuit coupled thereto and tuned to waves of the desired carrier frequency, and means having inductive reactance connected in one side only of said secondary circuit for excluding energy of undesired frequency.
5. A radio receiving system comprising a closed antenna circuit, a secondary circuit connected thereto and a closed loop having inductive reactance at desired frequencies in said secondary circuit anti-resonant at the frequency of undesired waves for excluding said undesired waves.
6. A radio receiving system comprising a closed antenna circuit, a secondary circuit coupled thereto and tuned to the waves of the desired carrier frequency, and a closed loop having inductive reactance at desired frequencies in said secondary circuit anti-resonant at the frequency of undesired waves for excluding said waves.
7. A radio receiving system comprising an antenna circuit including a loop antenna, a secondary circuit connected thereto, and a closed loop inductively reactive at desired frequencies connected in series in said secondary circuit and tuned to the frequency of waves which it is desired to exclude.
8. A radio receiving system comprising an antenna circuit including a loop antenna, a secondary circuit coupled thereto and tuned to waves of the desired carrier frequency, and a closed loop having inductive reactance at desired frequencies in series in said secondary circuit and tuned to the frequency of waves which it is desired to exclude.
9. A radio receiving system comprising a closed antenna circuit, a secondary circuit connected thereto, a radio transmitting station for transmitting waves of a frequency

other than that which it is desired to receive, and means having inductive reactance at desired frequencies in said secondary circuit for excluding waves transmitted from said radio transmitting station.

10. A radio receiving system comprising a circuit including a loop antenna, a secondary circuit coupled to said first named circuit and tuned to waves of the desired carrier frequency, a radio transmitting station for transmitting waves of a frequency other than that which it is desired to receive, and means in said secondary circuit comprising a closed loop having inductive reactance at desired frequencies anti-resonant at the frequency of the waves transmitted from said transmitting station for excluding said waves.

11. A low frequency transmission line, a radio transmitting station for transmitting carrier waves modified in accordance with electrical impulses transmitted over said line, a radio receiving station comprising a closed antenna circuit, a secondary circuit coupled thereto and tuned to waves of a carrier frequency other than that of said radio transmitting station, a closed loop in said secondary circuit anti-resonant at the frequency of the waves transmitted from said transmitting station, and means for impressing upon said line impulses obtained by demodulating the waves received by said radio receiving station.

12. A radio toll link comprising transmitting and receiving apparatus constituting two channels for oppositely directed transmission, one channel being selective for carrier waves of one frequency and the other channel for carrier waves of higher frequency, the higher frequency channel including a loop antenna and a circuit in series therewith anti-resonant at the carrier wave frequency of the lower frequency channel.

13. A radio toll link comprising transmitting and receiving apparatus constituting two channels for oppositely directed transmission, one channel being selected for carrier waves of one frequency and the other channel for carrier waves of a different frequency, a tuned receiving circuit in the lower frequency channel, a secondary circuit coupled to said receiving circuit, a loop antenna in said receiving circuit, and a loop anti-resonant at the high carrier frequency in said secondary circuit.

14. A radio toll link comprising two oppositely directed radio transmission channels, one channel being selective for carrier waves of one frequency and the other channel for carrier waves of a different frequency each channel comprising a primary receiving circuit and a secondary receiving circuit coupled thereto, each of said primary circuits including a loop antenna, and

a closed loop anti-resonant at the carrier frequency of the oppositely directed channel in the primary circuit of one channel and in the secondary circuit of the other channel.

15. In a radio receiving system, an antenna impressed with desired and undesired waves, a secondary circuit coupled to said antenna, a detector and a receiving device and means in said secondary circuit

including an inductance and a capacity for excluding waves of undesired frequency from said receiving device, the reactance of said inductance being such as to predominate over the reactance of said capacity 15 at the frequency of desired waves.

In witness whereof, I hereunto subscribe my name this 5th day of August A. D., 1921.

FRANCIS M. RYAN.
